UNITED STATES PATENT OFFICE.

FREDERICK FRASER MILLER, OF NAPANEE, ONTARIO, CANADA.

INTERNAL-COMBUSTION ENGINE.

1,110,332.

Specification of Letters Patent. Patented Sept. 15, 1914.

Application filed November 14, 1913. Serial No. 801,095.

To all whom it may concern:

Be it known that I, FREDERICK FRASER MILLER, residing in the town of Napanee, in the counties of Lennox and Addington, in the Province of Ontario, Canada, have invented certain new and useful Improvements in Internal-Combustion Engines, of which the following is the specification.

My invention relates to improvements in internal combustion engines and the object of the invention is to provide a means whereby the explosive mixture used in such engines is more uniformly and thoroughly mixed; and it consists essentially of a deflecting wing secured to and forming the top of the piston and provided at its center with an outwardly extending wedge shaped projection the apex of which is opposite the orifice of the intake pipe of the carburetor as hereinafter more particularly explained.

Figure 1, is a sectional elevation of the cylinder and piston. Fig. 2, is a sectional plan of the cylinder and piston.

Like letters of reference refer to like parts in the several drawings.

A is the cylinder having the usual water jacket A'.

A² is the piston with the connecting rod A⁸ attached thereto.

A³ is a wing formed on the top face A⁹ of the piston A² at any desired distance from the periphery of the piston.

A⁴ is a wedge shaped projection of the wing A³.

B is an external pump or carburetor by means of which the hydrocarbon fluid is sprayed into the cylinder A through the discharge pipe B', which passes through the cylinder walls and is exactly opposite the apex of the wedge projection A⁴ when the piston A² is at the extreme inward stroke.

A⁶ is the air inlet bypass connected with the inlet port opening A⁷.

The stream of hydrocarbon fluid as it is sprayed into the cylinder A impinges on the apex of the wedge shaped projection A⁴ is thereby divided and deflected on the opposite sides of the wedge piece A⁴. The curved faces of the wedge shaped piece A⁴ gives the

fluid a whirling motion and this fluid meeting the inflowing air in the inlet port opening A⁷ mixes with the air and carries the mixture so formed upwardly with a whirling motion and forming a complete mixture.

From this description it will be seen that I have devised a simple device whereby a thorough mixture of hydrocarbon fluid and air is brought about.

What I claim as my invention is.

1. In an internal combustion engine, the combination with the cylinder provided with an inlet port through which the fuel is designed to be received, of a piston having a wing extending across the top face, a projection extending from the wing opposite the inlet port of the cylinder whereby the incoming stream of fuel is deflected with a swirling motion toward each side of the cylinder, as and for the purpose specified.

2. In an internal combustion engine, the combination with the cylinder provided with an inlet port through which the fuel is designed to be received, of a piston having a wing extending across the top face, a wedge shaped projection extending from the wing, the apex of the projection being opposite the inlet port of the cylinder whereby the inflowing stream of fuel is divided and directed to flow upwardly toward each side of the cylinder, as and for the purpose specified.

3. In an internal combustion engine, the combination with the cylinder provided with an inlet port through which the fuel is designed to be received, of a piston having a wing extending across the top face, a wedge shape projection having curved sides extending from the wing, the apex of the projection being opposite the inlet port of the cylinder whereby the inflowing stream of fluid is divided to flow upwardly with a whirling motion toward each side of the cylinder, as and for the purpose specified.

FREDERICK FRASER MILLER.
